(57) CLAIM

The ornamental design for a work light, as shown and described.

DESCRIPTION

FIG. 1 is a front, top and right-side perspective view of a work light showing my new design;

FIG. 2 is a front view thereof;

FIG. 3 is a rear view thereof;

FIG. 4 is a top view thereof;

FIG. 5 is a bottom view thereof;

FIG. 6 is a right-side view thereof, with the left-side view being a mirror image thereof;

FIG. 7 is an in-use, reference front view thereof; and,

FIG. 8 is an in-use, another reference front view thereof.

The broken lines shown represent unclaimed subject matter of the work light and form no part of the claimed design.

1 Claim, 8 Drawing Sheets
